UNITED STATES PATENT OFFICE.

GERALD CAHILL, OF LOWELL, MASSACHUSETTS, ASSIGNOR, BY MESNE ASSIGNMENTS, TO WINCHESTER REPEATING ARMS COMPANY, OF NEW HAVEN, CONNECTICUT, A CORPORATION OF CONNECTICUT.

HEAT-INTERCHANGE APPARATUS AND METHOD OF CONSTRUCTING THE SAME.

Application filed March 12, 1926. Serial No. 94,274.

This invention relates to heat interchange apparatus and more particularly to apparatus comprising a fluid containing chamber separated from a second fluid containing space by a series of relatively thin contacting walls, such, for example, as may be afforded by a cellular or tubular structure, through which a fluid may be caused to circulate and to effect a heat interchange with a second fluid in contact with the opposite sides of the walls thereof.

In constructing such an apparatus it is customary to form a core by the assemblage of thin walled tubular conduits having enlarged ends arranged in closely fitting relation and bonded together to form pressure fluid tight front and rear walls, the sides of such structure being closed in by suitable side walls also bonded to the enlarged tubular ends to form pressure fluid tight joints thereat. It is often required to equip such a structure with a chamber at the inlet or outlet ends, or both, in the form of a header comprising a tank or box-like compartment, the walls of which are relatively thick as compared with the walls of the tubular conduits.

Such a header, where it forms the top or bottom of the structure, must also be bonded to the tubular members, and where it is attached directly thereto as a subsequent operation to the bonding of the tubes, it requires the application of such high heat that the soldered joints of the adjacent tubes tend to be weakened.

One object of the invention is to provide such a construction that the attachment of the header may be effected without weakening the adjacent soldered joints of the tubes.

The invention will be best understood by reference to the following description when taken in connection with the accompanying illustration of one specific embodiment thereof, while its scope will be more particularly pointed out in the appended claims.

In the drawings,

Fig. 1 is a plan view of a heat interchange apparatus embodying one form of the invention with the header tank removed;

Fig. 2 is a front elevation in partial section of the apparatus shown in Fig. 1, with both the inlet and return headers in position; and

Fig. 3 is a cross sectional elevation on the line 3-3 in Fig. 2.

Referring to the drawings and to the illustrative embodiment of the invention, I have there shown a heat interchange apparatus in the form of a heater comprising a steam chamber traversed by a multiplicity of air circulation tubes, the tubes being assembled in such form to constitute a cellular or tubular heater for heating the air through the utilization of live steam. The body of the heater is prepared by assembling a group of tubes 5, the latter being preferably thin walled and formed of copper, brass or other suitable metal. The main body of each tube is of circular cross section, but at each opposite end it is enlarged for a short distance into a head 7 non-circular or polygonal in cross section, and herein hexagonal in shape. The heads when grouped or assembled are arranged in close fitting contacting relation, while the intermediate portions of reduced circular cross section are separated by narrow connecting spaces 9 forming in the aggregate the steam heating chamber.

A group of such tubes are assembled in any desired geometrical arrangement, such as the rectangular form herein shown, the sides of the heater being closed in by any suitable means. Herein the sides are formed by the two side closing strips 11 of copper or other suitable metal, and of a width substantially coextensive with the length of the tubes, each strip being formed with corrugations or channels which fit over and against the contour of the hexagonal heads of the tubes, as shown in Fig. 2.

The depressions in the side closing strips 11 are filled with tubular members fitting the same, herein in the approximate cross sectional form of a D, thereby providing a substantially flat side against which there is placed a side stiffening plate 13. The latter, together with the closing strips 11, extends slightly beyond the assembled tubes both at the top and bottom of the heater. The enlarged ends of the tubes in the top and bottom row are preferably given such a cross sectional shape (herein pentagonal) as to provide a flat top or bottom wall or shelf at the front and rear sides to which the header tank 15 may be secured.

The header comprises top and side walls,

the latter with inturned bottom edges, the header having the inlet connection 17 in the top wall and the deflecting plate 19 immediately below the inlet connection. The 5 header has an open bottom and provides a compartment or space opening into the tubular heating space below. The outlet or return header at the bottom of the heater is similarly constructed. Instead, however, of 10 assembling the header tanks with the their relatively thick walls in direct contact with the tubular structure described, I interpose between the thick-walled header and the thin-walled tubes intermediate separating 15 strips of metal of a thickness less than the thickness of the walls of the header and preferably approximating as nearly as possible the density and thickness of the metal of the tubes.

20 In the disclosed embodiment of the invention these intermediate metallic strips are provided by the walls of a false or skeleton tank 21 having box-like sides adapted to fit between the projecting ends of the strip 11 25 and presenting a space into which the sides of the header tank 15 fit and may be inserted. The bottom of the skeleton tank has openings 23 of ample area to prevent any obstruction of the flow of steam from the header 30 into the heating chamber, the openings being separated by stiffening portions 25 which add to the rigidity and strength of the structure.

In constructing the heater the parts are 35 first assembled and bonded without the top and bottom headers. Preferably the entire structure, omitting the headers and including the tubes, the side closing strips 11, stiffening strips 13 and skeleton tanks 21 held 40 in closely fitting assembled relation as described, is subjected as an entirety to a single bonding operation. This may be accomplished by first successively dipping the opposite sides of the header structure into 45 a bath containing a suitable flux, such, for example, as one employing a zinc chloride base, after which the opposite sides of the assembled structure are dipped in a bath of melted solder, causing the latter to bind 50 together the various parts. The dipping process is preferably carried out so as to cause both the flux and solder to penetrate into the joints for a depth at least equal to the length of the hexagonal heads of the 55 tubes, the result being that the hexagonal heads are united with steam tight joints and all joints at the front and rear of the structure are similarly made pressure tight.

Since the false tanks are dipped with the 60 core or matrix composed of the tubes, and since the thickness of the walls of the false tanks approximate that of the tubes, a uniform and more enduring bond is effected than if it were attempted to bond the thick 65 walls of the header directly to the tubes,

this being due to the fact that where parts of widely varying thickness are bonded by the dipping process the temperature of the two members of different thickness between which the bond is to take place is apt to differ 70 widely and this results in an inferior bond. With the relatively thin walled parts of the skeleton tank contacting with the tubular core, however, the temperature of the parts sufficiently approaches the same point as to 75 provide a uniform and enduring bond.

The heavier expansion tanks or headers can now be attached by a separate soldering or bonding operation to the walls of the false or skeleton tank without danger of 80 transmitting sufficient heat to weaken the soldered joints of the adjacent tubes, thereby completing the construction of the heater.

I may construct the heater preparatory to 85 applying the headers by building it up through successive bonding operations, as by first bonding the tubes in the form of a matrix or core and then subsequently soldering to such core the closing strip, the stiffening strip, and then the false tanks, and finally soldering the header tanks in position. The interposition of the walls of the skeleton tank of a thickness or density intermediate that of the walls of the header tank 90 and the thin walls of the tube even, under this method of construction, affords the advantage of preventing such a transmission of heat to the thin walls of the tubes during the soldering of the header as would tend to 95 weaken the joints.

The presence of the skeleton tank also stiffens the construction of the assembled headers and tubes, preventing bulging and lessening the chances of the structure under 100 pressure tending to pull apart at the seams.

The use of the intermediate strips, herein in the form of the skeleton tank, however, has the important advantage that the entire structure, minus the headers, may be subjected to the single bonding operation by the dipping process, which I prefer to use, the subsequent bonding of the headers to the false tank being easily accomplished with the production of a uniform bond at all the 110 joints.

While I have herein shown and described for the purpose of illustration one specific embodiment of the invention, it is to be understood that the same may be varied 120 within wide limits, all without departing from the spirit thereof.

I claim:

1. A heat interchange apparatus having a 125 heat interchange chamber formed by a group of thin walled tubular members extending through the chamber and having opposite enlarged ends arranged in closely fitting relation and bonded together to form front and rear walls of the chamber, a relatively

thick walled header providing a fluid receiving chamber, and an intermediate member bonded to the tubes and to which said header is bonded, said intermediate member comprising a skeleton tank with box-like sides in which said header fits.

2. A heat interchange apparatus having a heat interchange chamber formed by a group of thin walled tubular members extending 10 through the chamber and having opposite enlarged ends arranged in closely fitting relation and bonded together to form front and rear walls of the chamber, a fluid receiving chamber at one end of the apparatus 15 having relatively thick walls, and a member interposed between and separating the walls of the thick walled member from the enlarged ends of the thin walled tubes and more particularly approximating the thickness 20 of the latter, said tubes, intermediate member and thick walled chamber being bonded together to form fluid tight joints, whereby said tubes and intermediate member may be bonded together by one bonding

operation and the thick walled chamber 25 bonded to the intermediate member by another bonding operation.

3. A heat interchange apparatus comprising a core formed of thin walled tubular members, a relatively thick walled header 30 presenting a fluid receiving chamber at one end of the apparatus, and a skeleton member having walls of a thickness more nearly approximating the thickness of the walls of the tubular members interposed between and 35 separating the walls of the thick walled header from the thin walled tubular members and serving to brace the structure, said parts being bonded together to form fluid tight joints, whereby the tubular members 40 and the skeleton member may be bonded together by one bonding operation and the skeleton member bonded to the thick walled header by another bonding operation.

In testimony whereof, I have signed my 45 name to this specification.

GERALD CAHILL.
